UNITED STATES PATENT OFFICE.

JOSEPH O. OSTMAN, OF BROOKLYN, NEW YORK.

ADJUSTABLE PRINTER'S GALLEY.

1,159,260.

Specification of Letters Patent.

Patented Nov. 2, 1915.

Application filed March 24, 1915. Serial No. 16,693.

To all whom it may concern:

Be it known that I, JOSEPH O. OSTMAN, a citizen of the United States, residing at Brooklyn, in the county of Kings and State 5 of New York, have invented certain new and useful Improvements in Adjustable Printers' Galleys; and I do hereby declare the following to be a full, clear, and exact description of the invention, such as will enable others skilled in the art to which it 10 appertains to make and use the same.

This invention relates to adjustable gal- 15 leys for use by compositors and printers, and one of the principal objects of the in- vention is to provide a galley having an ad- justing bar and a locking bar, said adjusting bar adapted to be moved longitudinally of the galley to provide for any width of 20 column of type to be set, and said locking bar adapted to be adjusted against the last line of type in the job or form to lock the same in place.

Another object of the invention is to pro- 25 vide a printer's galley which can be ad- justed to any width of column within the limits of the galley and which will be pro- 30 vided with means for firmly locking the printed matter in place when it has been set and placed on the galley.

Still another object of the invention is to 35 provide a printer's galley in which various shapes of forms may be set in which the lines are of increasing or decreasing lengths progressively, and means being provided for 40 locking the form and means being provided also for determining the width of the column by graduating marks on the marginal flanges of the galley and also upon the ad- justing bar and locking bar, said graduated 45 marks being arranged in standard point printers measure, that is to say, 72 points or six picas to the inch.

The foregoing and other objects may be 50 attained by means of the construction illus- trated in the accompanying drawings, in 55 which—

Figure 1 is a top plan view of a galley made in accordance with this invention, Fig. 2 is an end or edge view of the galley, Fig. 3 50 is a side elevation of the galley, Fig. 4 is a perspective view of the adjustable or gage bar, Fig. 5 is a side elevation of the locking bar shown broken away in the center, and Fig. 6 is a detail sectional view of the lock- 55 ing end of the locking bar.

Referring to the drawings, the numeral 1

designates the base of the galley, which is usually made of brass of the required thick- 60 ness and gage, and the marginal sides and ends of the galley in this instance comprise a channel bar of substantially U-shape in cross section, the side bars being designated by the numeral 2, and the end bar by the numeral 3. The side bars or members 2 are secured to the bottom 1 by means of rivets 4, 65 and at the corners rivets 5 secure the over- lapsing ends of the sides and end bars 3. The side bars 2 are provided with a line of perforations 6 extending nearly from end to end of said side bars and spaced apart the 70 distance of one or two picas, while the end bar 3 is also provided with perforations 7 which extend nearly the full length of said bar and are also spaced apart a distance equal to one or two picas. The upper sur- 75 face of the side bars 2 is provided with graduation marks 8 in points and the end bar 3 is also provided with graduating marks 9.

The locking bar comprises the two parallel 80 members made of slightly resilient metal and said members 10 being spaced apart by means of a block 11 near one end and a flange or spacer 12 at the opposite end while a block 13, forming a housing for a bolt to be 85 hereinafter described also serves to hold the members 10 the required distance apart. Connected to the upper bar or member 10 and projecting inwardly toward the oppo- 90 site bar is a series of studs or pins 14, said pins being preferably spaced apart the width of two picas. A sliding bolt 15 is mounted in the block 13 and provided with a spring 16 which projects the bolt 15 through the block 11 and through the side member 2, as shown 95 more clearly in Fig. 6. A finger hold 17 is disposed in the space between the block 11 and the block 13. The bolt 15 projects through any of the openings 6 in the side member 2, while at the opposite end of the locking bar is a projecting pin 18 which fits in any of the holes 6 in the opposite side bar.

The gage bar 19 is of a thickness to ex- 100 tend between the two bars 10 of the locking member, and at the opposite end of the gage bar 19 spacers 20 are secured underneath the bar to hold said bar in alinement with the space between the two members 10. A pin 21 projects from one end of the gage 105 bar and said pin is adapted to be inserted in any one of the holes 7 in the end mem-

bers 3, while the pins 14 on the locking bar are adapted to enter any one of a series of holes 22 in the gage bar, said holes being spaced apart the distance of a pica or two, 5 as the case may be. The locking bar is provided with graduation marks *a* on the upper member, and the gage bar 19 is provided with graduation marks *b* on the scale point measure.

10 From the foregoing it will be obvious that the gage bar 19 may be adjusted transversely of the galley at any point between the two members of the locking bar and held in position by the stud 14 to provide 15 any width of column desired, and after the type has been set and placed on the galley it may be locked by moving the locking bar 10 up against the foot of the form. It will also be obvious that the gage bar 19 may be 20 adjusted at an angle by placing the pin at one point in the end member 3 of the galley frame and securing it at the required angle to one of the studs 14 of the locking bar.

Various changes may be made in the 25 details of construction without departing from the spirit and scope of the invention as defined in the claim.

What is claimed is:—

30 A printer's galley provided with a marginal frame having a series of perforations therein, a longitudinal extending locking bar comprising a pair of parallel members,

a series of downwardly extending pins arranged on the inner face of the upper member, blocks disposed between and adjacent the ends of the parallel members thereby spacing said members, one of said blocks having a longitudinal aperture therein, and the other an outwardly extending stud, a recess block adjacent said apertured block, 35 a spring catch bolt slidably mounted in said recess block and adapted to extend through said apertured block, a finger hold on said bolt adapted to bear against said apertured block thereby limiting the movement of the 40 same, whereby said locking bar is adapted to be vertically adjustable on said frame, a vertical gage bar having a series of apertures formed therein, said gage bar being adapted to extend through the said parallel 45 members of the locking bar whereby one of said pins on the upper member can engage in one of said apertures in the gage bar, thereby locking the gage bar, and a stud on the end of said gage bar adapted to engage in one of the apertures in the galley in the 50 marginal frame, whereby a form can be locked on the galley.

In testimony whereof I affix my signature in presence of two witnesses.

JOSEPH O. OSTMAN.
